US00D981988S

(12) **United States Design Patent** (10) **Patent No.:** **US D981,988 S**
Bellham et al. (45) **Date of Patent:** ** *Mar. 28, 2023

(54) **HEADPHONES**(71) Applicant: **GN AUDIO A/S**, Ballerup (DK)(72) Inventors: **Philip Bellham**, Ballerup (DK);
Rasmus Trudslev Pedersen, Ballerup (DK);
Bill Zeng, Ballerup (DK)(73) Assignee: **GN AUDIO A/S**, Ballerup (DK)

(*) Notice: This patent is subject to a terminal disclaimer.

(**) Term: **15 Years**(21) Appl. No.: **29/828,887**(22) Filed: **Mar. 1, 2022****Related U.S. Application Data**

(63) Continuation of application No. 29/738,543, filed on Jun. 18, 2020, now Pat. No. Des. 944,765.

Primary Examiner — Paula Allen Greene*(74) Attorney, Agent, or Firm* — Hamre, Schumann, Mueller & Larson, P.C.(57) **CLAIM**

The ornamental design for a headphones, as shown and described.

DESCRIPTION

FIG. 1 is a top perspective view of headphones showing the new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.
